UNITED STATES PATENT OFFICE.

EDWIN ANDERSON MCKOY, OF NEW ORLEANS, LOUISIANA.

TURPENTINE-CUP.

942,210.

Specification of Letters Patent.

Patented Dec. 7, 1909.

Application filed June 10, 1907. Serial No. 378,204.

To all whom it may concern:

Be it known that I, EDWIN ANDERSON MCKOY, a citizen of the United States, residing at New Orleans, in the parish of Orleans and 5 State of Louisiana, have invented certain new and useful Improvements in Turpentine-Cups; and I do hereby declare the following to be a full, clear, and exact description of the invention, such as will enable others skilled 10 in the art to which it appertains to make and use the same.

This invention relates to means for collecting sap, especially pitch for turpentine manufacture, and has for an object to provide an 15 apron of improved construction adapted to be attached to a turpentine bearing tree.

A further object of the invention is to provide an apron having one or more slots formed longitudinally thereof and through 20 which the sap may enter a receptacle therebeneath.

With these and other objects in view, the 25 invention comprises certain novel constructions, combinations and arrangements of parts, as will be hereinafter fully described and claimed.

In the drawings: Figure 1 is a view of the 30 device in side elevation applied to a turpentine bearing tree. Fig. 2 is a view in perspective of one embodiment of the improved apron. Fig. 3 is a perspective view of an 35 apron similar to Fig. 2 with the slots omitted.

Like characters of reference designate corresponding parts throughout the several 40 views.

The apron forming the subject-matter of 45 this application comprises a substantially plain portion 10 preferably provided with 40 upturned flanges 11 at its opposite ends and with the slots 12 cut therethrough when such slots are found desirable. The apron is provided with any improved form of upper or long edge as the concave 13, whereby such 50 edge conforms substantially to the periphery of the tree.

The flanges 11 are provided substantially 55 mid-way with means for suspending a cup, such means embodying the notches 14 cut in said flanges, as shown particularly in Figs. 2 and 3.

For use in association with the apron above described a receptacle 15 is preferably 60 employed having its opposite ends 17 provided with upstanding arms 18 which are 65 preferably formed integral with the said

ends and with hooks 19 adapted to hook into the notches 14 to so position the receptacle beneath the apron that practically the entire area of the receptacle is covered by 70 such apron.

As shown in Fig. 1 it will be seen that the receptacle being substantially covered by the apron sap will drip from the lower edge into the side of the bucket or receptacle, whereas if slots 12 are provided as shown in Fig. 2, the major portion of such sap will drip through the slots into the receptacle before reaching the edge of the apron. The object of providing the receptacle proportioned to be covered substantially by the apron is to prevent chips and other extraneous matter from falling into the receptacle, especially while fresh wood is being exposed by chopping the bark. It 75 is well known that there are a large number of different grades of turpentine, such 80 grades depending very largely, if not exclusively, upon the amount of extraneous matter contained in the pitch at the time of boiling, such extraneous matter changing 85 not only the consistency and properties of the turpentine, but the color as well. Notwithstanding the desirability of covering the receptacle it is, of course, absolutely necessary 90 that the apron surface be exposed as a considerable portion of the pitch or sap does not run down the tree onto the apron but drops in large drops from the fresh wood above the apron directly upon 95 the apron without following the course of the wood from the cut to the apron. It is, therefore, as before explained, necessary 100 that the apron be exposed to catch the dripping sap and to conduct it to the receptacle. By the employment of an apron provided with the slots, as shown in Fig. 2, the bark, chips and other extraneous matter is caught upon the apron but slides therefrom and is discharged from the edge rather than 105 into the receptacle below.

While the apron shown at Figs. 2 and 3 is provided with concave upper edges it is to be understood that the utility of the invention is not dependent upon such curved 110 edge as edges of different conformations may be employed, as found desirable in practice.

What I claim is:—

1. In a device of the class described, an 110 apron provided with an opening extending longitudinally thereof.

2. In a device of the class described, an apron provided with a slot extending longitudinally thereof.
3. In a device of the class described, an 5 apron provided with flanges formed at its opposite ends, and a slot extending longitudinally of the apron and between the flanges.
4. In a device of the class described, an 10 apron provided with a longitudinally extending slot, and a receptacle adapted to be suspended from the apron and beneath the slot.
5. In a device of the class described, an 15 apron, flanges formed upon opposite ends of the apron, a slot formed longitudinally of the apron and between the flanges, and a receptacle proportioned to be suspended from the flanges and beneath the slot.
- 20 6. A device of the class described including an inclined supporting apron having a discharge opening and provided with oppo-
- sitely disposed guide flanges, and a receptacle depending from the apron at said discharge opening. 25
7. A device of the class described including a supporting member having one longitudinal edge thereof curved inwardly and its opposite edges bent upwardly to form spaced guide flanges, there being a discharge opening formed in the supporting member, and a receptacle detachably secured to the supporting member beneath the discharge opening. 30
8. An apron having upturned flanges at 35 opposite ends, and receptacle-engaging notches formed intermediate the ends of the flanges.

In testimony whereof I affix my signature in presence of two witnesses.

EDWIN ANDERSON McKOY.
